CONVERTIBLE FOLDING TRAY TABLE AND COFFEE TABLE

John B. Adler, Grosse Ile, Mich., assignor to Shwayder Brothers, Denver, Colo., a corporation of Colorado

Application March 1, 1951, Serial No. 213,363

2 Claims. (Cl. 311—79)

1

This invention relates to folding tray table and more particularly to a folding standard of X shape and having a removable tray.

It is the object of the present invention to provide a novel folding tray table wherein a pair of hollow, rectangularly shaped supporting elements are pivotally joined together intermediate their ends to provide a tray support across their upper ends.

The further object of this invention is to provide a novel tray construction whereby said tray may be removably snapped onto the upper portions of the cross supports, and wherein said tray may be removed and said supports turned 10 90 degrees upon one of their side members, and wherein said tray may be repositioned upon the other of said side members to provide a coffee table.

These and other objects will be seen from the following specification and claims in conjunction 20 with the appended drawings in which:

Fig. 1 is a partially broken away and sectioned elevational view of the folding tray table.

Fig. 2 is a right side elevational view thereof with a portion of the tray broken away and sectioned.

Fig. 3 is a perspective view of the folding tray table.

Fig. 4 is an enlarged fragmentary view of a pair of adjacent supporting members with the stop bracket illustrated.

Fig. 5 is an enlarged fragmentary section illustrating the relation between the upper end of the tray support and the spring clip upon the tray in cooperation therewith.

Fig. 6 is a plan view of the folding tray table as converted to a coffee-table with the supports therefor having been rotated 90 degrees forwardly from the position shown in Fig. 3.

Fig. 7 is a front elevational view of the table shown in Fig. 6 with a portion of the tray broken away and sectioned to illustrate its relation to the support therefor; and

Fig. 8 is a perspective view of the table shown in Figs. 6 and 7.

It will be understood that the above drawings illustrate merely a preferred embodiment of the invention and that other embodiments are contemplated within the scope of the claims hereafter set out.

Referring to the drawings the folding tray table shown in Figs. 1, 2 and 3 consists of a pair of preferably tubular hollow rectangularly shaped supports 11 and 12 pivotally joined to each other at 13 intermediate their respective ends.

The lower parallel spaced supporting elements

2

14 and 15 form a part of supports 11 and 12 respectively and are adapted to bear upon any horizontal surface.

The formed tray 16 has a peripheral ridge 17 throughout its outer portion which terminates in the depending peripheral flange 18 which is provided with an upturned lower flange 24 as shown in Fig. 1 to afford additional rigidity to the tray and to provide a finished lower surface or edge.

As shown in Fig. 2 a spacer 19 is interposed between the supports 11 and 12 upon one side thereof and a stop 20 is interposed between the other two support elements upon the opposite side thereof.

The upper parallel spaced cross bars 19' and 20' at the upper ends of supports 11 and 12 provide a horizontal and sturdy support for tray 16 whose under surface is adapted to bear directly upon said cross bars.

There is provided a suitable stop bracket 20 shown enlarged in Fig. 4 which has a transverse arcuate slot 22 and which is secured at one side to the support 12 as by the rivet 21 and is secured also to the rivet or pivot pin 13 between supports 11 and 12. Pin or rivet 23 projects through support 11 and also through the arcuate slot 22 of stop bracket 20 and is adapted for sliding movement within said slot to limit the outward expansion of the X-shaped supports and also to permit their collapsing as desired.

A pair of spring clips 25 depend from spaced central portions of the under surface of tray 16 and are suitably secured thereto by the clip flanges 26, preferably welded to the under surface of tray 16.

Said spring clips include the resilient horizontally and inwardly directed portions 27 which terminate in the outturned guide flanges 28 whereby said tray may be snapped over and upon the cross rods 19' and 20' in the manner illustrated in Fig. 1, and with said spring clips 25 removably and retainingly engaging said upper ends of the supports 11 and 12.

In view of the outturned flanges 28 the snapping on of the tray 16 is facilitated, said clips being effective for securing said tray in position as shown in Figs. 1 and 3.

As shown in Fig. 2 the lower cross supports 14 and 15 are slightly offset so as to define at their opposite ends the surface engaging and supporting elements 29. Furthermore one of the side elements of each hinged pair of supports 11 and 12 is inwardly offset to thereby provide at their respective ends a curved supporting element 30 hereafter described in further detail.

Referring to Figs. 6, 7, and 8 the X shaped sup-

port shown in Fig. 3 has been revolved 90 degrees so that the side portions of the supports 11 and 12 of Fig. 3 now provide the bottom supports for the converted coffee table.

As above described one of the sides of support 12 is offset to thereby provide the end supports 30, and as shown in Fig. 8 said end supports co-operate with the bottom surface of support 11 to thereby provide a rigid non-tipping support for the table in the position shown.

Similarly as above described one of the other side portions of the support 11 is also offset to provide the rounded end supports 31, the upper portions of which are coplanar with the top surface of the adjacent support element 12 to thereby provide a rigid support for the tray 16 as illustrated in Fig. 7.

In the converted position of the tray table the under surface 32 of tray 16 bears upon the support elements 31 and upon the support element 12, and at the same time the tray is so constructed that the respective curved ends of the supports 11 and 12 project snugly into the interior corners of said tray upon its under side and with the flange 18 cooperatively bearing against lateral portions of said rounded ends.

Thus by this construction the tray 16 is firmly and effectively secured upon the supports 11 and 12 as illustrated in Figs. 7 and 8 to thereby provide a versatile tray table which may be quickly converted from the form shown in Fig. 3 to the form shown in Fig. 8.

Having described my invention reference should now be had to the claims which follow for determining the scope thereof.

I claim:

1. A foldable tray table comprising a pair of hollow rectangularly shaped supports, with their respective sides pivotally connected intermediate their ends to form an X shape, the upper horizontal ends of said supports being spaced from each other, and a tray positioned and secured upon said spaced ends and adapted for complete removal therefrom, said supports being adapted for tipping 90 degrees whereby one of the pivotally connected sides of said supports rests upon a supporting surface, said tray being retainingly positioned upon and over the other side portions of said pivotally connected supports, said tray having a depending peripheral flange, and said tray and said flange being of such size that the interior corners of said flanges snugly and retainingly engage over the opposite end portions of the adjacent sides of said supports, an arcuately slotted stop bracket secured upon one of said sides of one of said supports adjacent its pivotal connection, and a headed pin extending through the slot of said bracket and secured to an adjacent

side of the other support, limiting the pivotal opening movements of said supports facilitating assembly of said tray with respect to said spaced ends and assembly of said flange around said end portions.

2. A foldable tray table comprising a pair of hollow rectangularly shaped supports, with their respective sides pivotally connected intermediate their ends to form an X shape, the upper horizontal ends of said supports being spaced from each other, a tray removably positioned upon said spaced ends, a pair of spaced opposed spring clips each secured to and depending from the undersurface of said tray at its central portion and arranged adjacent its opposite ends, each clip extending around the outside of and under the corresponding spaced end retainingly engaging the same, whereby said tray may be snapped over said ends and may be entirely removed therefrom, said supports being adapted for tipping 90 degrees whereby one of the pivotally connected sides of said supports rests upon a supporting surface, said tray being retainingly positioned upon and over the other side portions of said pivotally connected supports, said tray having a depending peripheral flange, and said tray and said flange being of such size that the interior corners of said flanges snugly and retainingly engage over the opposite end portions of the adjacent sides of said supports, an arcuately slotted stop bracket secured upon one of said sides of one of said supports adjacent its pivotal connection, and a headed pin extending through the slot of said bracket and secured to an adjacent side of the other support, limiting the pivotal opening movements of said supports providing a rigid structure independent of said tray and pre-determining the positions of said supports for cooperatively receiving said tray.

JOHN B. ADLER.
